UNITED STATES PATENT OFFICE

WALTER G. JONES, OF NEW YORK, N. Y.

PULL TOY

Application filed February 25, 1929. Serial No. 342,510.

The invention relates to toys of the character provided with wheels and adapted to be pulled by a cord, and has for its object to provide a toy in simulation of the motions of an animal as in walking or running.

According to one novel feature of this invention the legs of the animal are swingably associated with the body and extend downwardly over the outside of the wheels instead of between the wheels, and simple means is provided for imparting motion to the legs as the toy is pulled along the surface upon which it rests. Preferably the legs extend nearly to the bottom of the wheels, and the animal presents a very lifelike appearance due to the fact that the legs are in full view at all times and the wheels are practically hidden from sight as the legs swing back and forth, and, since the feet are close to the ground, the animal looks as if it is actually running on its legs instead of rolling on the wheels.

Another feature is the provision of novel means for wagging the tail of the animal in combination with the leg motion, whereby the toy resembles a running animal wagging its tail.

The nature of the invention and its distinguishing features and advantages will more clearly appear as the description proceeds.

Reference is to be had to the accompanying drawing forming a part of this specification, it being understood that the drawing is merely illustrative of one practical embodiment of the invention.

Figure 1 is a side elevation, with a portion broken away, of the toy animal made in accordance with the invention;

Figure 2 is a transverse section on the line 2-2 of Figure 1; and

Figure 3 is a modification partly broken away, and Figure 4 is a cross section of one leg thereof.

Referring at first more particularly to Figure 1, the numeral 1 indicates the body of the toy animal which may be of any suitable material such as wood turned to shape and provided with a head 2 which also may be turned and secured to one end of the body 1 in

any manner found desirable, such as by a pin or other fastener, but it is obvious that the head 2 may be formed as an integral part of the body 1. The body is supported upon four wheels, namely, front wheels 3 and rear wheels 4. The front wheels 3 are mounted on a shaft 5 which is journaled in a bracket 6 suitably secured to the body 1. The rear wheels 4 are secured to a crank-shaft 7 which also may be journaled in a similar bracket 6 adjacent the rear of the body 1, and it is preferable that the outer faces of the wheels 3 and 4 lie within a plane extending perpendicularly from the sides of the body 1, as will appear from an inspection of Figure 2. The legs 8 are each provided with a perforation 9 for a fastener 10 by means of which the leg is swingably secured to body 1, clear of the wheels. Each leg 8 also has a lengthwise groove 11, and a pin 12 projects from the outside face of the adjacent wheel, forming a pin-and-slot driving connection. The shaft 5 and the crank-shaft 7 are preferably secured against turning within their respective wheels 3 and 4 by squaring the ends of the two shafts or in any other practical way, and the pins 12 are preferably at diametrically opposite points on their respective sets of wheels 3 and 4, so that as the toy is pulled along by a cord C the legs on the opposite sides of the pairs of wheels will be given swinging motions alternately in opposite directions in simulation of the legs of an animal as in walking or running. It is to be noted that placement of the legs over the outermost faces of the wheels enables a full and unobstructed view of the legs at all times, and, by reason of the fact that the legs extend downwardly nearly to the surface 13 upon which the animal is being pulled, the wheels are practically obscured from sight as the legs swing rapidly back and forth at the sides of the wheels, and the toy appears to be running on its legs instead of rolling on the wheels.

A further amusing feature comprises a tail 14 which may consist of a piece of rope having one end thereof secured to the body 1 as by gluing into an opening. The tail is given a wagging motion up and down by connect-

ing the same to the crank-shaft 7 by a link 15 fastened to the tail as at 16 and operatively connected to the crank-shaft as at 17.

It is evident from the foregoing description that the oppositely disposed pairs of legs 8 will move alternately in opposite directions at the sides of the wheels as the tail 14 is wagged up and down, and the toy assumes a very lifelike and amusing appearance. Although the leg motion set forth above is preferable it is obvious that each of the legs may if desired be mounted for independent motion by having the wheels independently turnable on their shafts instead of fixedly secured thereto. This applies to all of the wheels except one of the rear wheels which must of course be tightly attached to the end of the crank-shaft 7 in order to operate the tail 14.

As an alternative the toy may include a stuffed body 18 having a frame 19 secured at the front and the rear of the body, the two frames being connected together by a bar 20, and the legs pivoted as indicated at 22. The legs 21 also may be stuffed and the pin-and-slot connection for driving the legs may comprise a channel strip 23 fastened to the inner side of each leg as by riveting or other fastening means, and cooperating with a headed pin 24 driven into the adjacent wheel 25.

In conclusion it is to be understood that while the illustrated example constitutes one practical embodiment of the invention it is not limited to the exact details set forth, since, manifestly, the same may be considerably varied without departing from the spirit of the invention as defined in the appended claims.

Having thus described my invention, I claim:

1. A toy animal comprising a body, a pair of front legs and a pair of rear legs pivotally mounted at the sides of the body, two wheels disposed between each pair of legs, a frame between the legs and adapted to connect said wheels to the body, each of said legs having a lengthwise slot facing the adjacent wheel, a pin carried eccentrically by each wheel and projecting into the slot of the leg, said legs being rigid from end to end and extending downward nearly to the plane of the surface upon which the wheels rest, a tail, a crank-shaft driven by the rear wheels, and a connection between the crank-shaft and the tail for wagging the same up and down as the wheels rotate.

2. A toy animal comprising a body, a pair of substantially U-shaped members secured in inverted position to the under side of said body, a shaft carried by the free ends of each of said members, a wheel mounted on the opposite end of each shaft, pairs of legs pivoted to the opposite sides of the body and extending over the outside of the wheels, each leg having a longitudinal slot facing the ad-

jacent wheel, and a pin secured eccentrically to each wheel and extending into the slot of the adjacent leg.

3. A toy animal comprising a body, wheels on which the toy is moved along the ground, a pair of front legs and a pair of rear legs pivotally mounted adjacent their upper ends at the sides of the body, the lower ends of the legs terminating at a point nearly in engagement with the ground, said wheels being disposed between the legs, and connections between the wheels and the legs arranged to impart positive oscillatory motions to the legs about their pivots on rotation of the wheels.

4. A toy animal comprising a body, wheels on which the toy is moved along the ground, a pair of front legs and a pair of rear legs pivotally mounted adjacent their upper ends at the sides of the body, the lower ends of the legs terminating at a point nearly in engagement with the ground, said wheels being disposed between the legs, connections between the wheels and the legs arranged to impart positive oscillatory motions to the legs about their pivots on rotation of the wheels, a tail, and means for wagging the tail in combination with the leg motion.

5. A toy animal comprising a body, wheels on which the toy is moved along the ground, a pair of front legs and a pair of rear legs pivotally mounted adjacent their upper ends at the sides of the body, the lower ends of the legs terminating at a point nearly in engagement with the ground, said wheels being disposed between the legs, and pin-and-slot connections between the wheels and the legs for imparting positive oscillatory motions to the legs about their pivots on rotation of the wheels.

6. A toy animal comprising a body, a pair of front legs and a pair of rear legs pivotally mounted adjacent their upper ends at the sides of the body, a pair of wheels disposed between each pair of legs, the lower ends of the legs terminating at a point nearly in engagement with the ground, connections between the wheels and the legs arranged to impart positive oscillatory motions to the legs about their pivots on rotation of the wheels, a tail, and means operated by the wheels for wagging the tail.

Signed at New York, county of Bronx, State of New York, this 23d day of February, 1929.

WALTER G. JONES.
